ELECTRON TUBE

Donald V. Edwards, Montclair, and Edward B. Van Note, Trenton, N. J., assignors to Electrons, Inc. of Delaware, a corporation of Delaware

Application May 17, 1938, Serial No. 208,336

2 Claims. (Cl. 250—27.5)

This invention relates to gaseous discharge tubes intended for operation at heavy currents and having a metal vacuum container.

The object is to provide a construction resulting in a small compact tube capable of radiating large quantities of heat.

In the accompanying drawing,

Fig. 1 is a view mostly in section, of a gaseous discharge tube comprising the invention;

10 Fig. 2 is a horizontal section on line 2—2 of Fig. 1, partly broken away; and

Fig. 3 is a perspective view of a modification of the tube of Fig. 1.

Like reference characters indicate corresponding parts in the several figures.

In Fig. 1 a gaseous discharge rectifier tube 10 has a metal envelope or container 11 closed by a metal bottom plate 12 which is formed with a trough-shaped sealing ring 13. Sealing material 14 secures the container and bottom plate together in sealed insulated relation. A cathode 15 is supported above plate 12, such as by rods 16 welded thereto, in discharge relation to container 11 which is also the anode of tube 10. The cathode illustrated is of the internal emissive type having an outer heat shield 17 and an inner can 18, each of which has an opening 19 for passage of the gaseous discharge to anode 11. The interior surface of can 18 may be electron emissive. It is provided with a heater 25 having multiple current paths between the top of can 18 and a metal plate 21. The heater itself may or may not be electron emissive depending on whether a directly heated or an indirectly heated cathode is desired. A lead-in conductor 20 for heater 25 is secured to plate 21 and passes through an insulating bushing 22 in the bottoms of can 18 and shield 17. Conductor 20 also passes through an inverted cup 24 to which it is sealed by welding, 40 and then through a large center hole 23 in plate 12 without touching the latter. The rim of cup 24 is sealed in the trough 13 by the sealing material 14 which may be of glass suitable for making a vacuum tight joint with metal.

45 Conductor 20 and plate 12 thus form terminals for the cathode and its heater. The heater circuit is from plate 12 through rods 16 to shield 17 and can 18, thence through heater 25 to plate 21 and back through conductor 20.

50 Electrical connections to tube 10 may be made as indicated diagrammatically in Fig. 1, the cathode connection and one heater connection being common. The anode connection to the container-anode 11 is made through metal members attached thereto as hereinafter described. It

should be understood that in practice such connections are large enough to carry the maximum current of tube 10, for instance, several hundred amperes for the cathode and anode connections.

5 In a large rectifier tube most of the energy losses in the tube are transmitted to the anode by the electron stream and must be dissipated to permit the tube to operate satisfactorily. Heretofore it has been the custom to depend upon radiation to convey substantially all of this heat 10 from the anode. Introduction of metal-wall containers permitted removing part of the heat by convection to the air and part by radiation to the surrounding atmosphere. For small tubes, radiation and convection can remove the heat 15 from the area where it is developed rapidly enough to prevent overheating. As the size of the tube is increased the anode area over which the energy is dissipated, has, in the past, been increased by lengthening the discharge path and 20 by increasing the cross section. To increase the area heated by the anode losses in large tubes results in a big cumbersome construction and increases the cost of the tube materially as the difficulties of manufacture increase in proportion 25 to the amount of surface that must be evacuated. In addition, the efficiency of the device is impaired because a much larger volume must be maintained in an ionized state resulting in a higher arc drop and therefore greater tube 30 losses.

According to the invention the tube size can be reduced to that giving the optimum discharge path as far as efficiency is concerned and allowing the anode losses to occur in a relatively small 35 area of the tube envelope, if the metal envelope is given a spheroid shape and if a radiator composed of material having a high heat conductivity is attached on to the outside, for instance, by the process described herein.

40 Such a radiator is shown at 26 in Figs. 1 and 2. It provides heat dissipation directly and radially by metallic conduction from every part of container-anode 11 that is subject to overheating. The radiator is made of metal having a 45 high heat conductivity and high coefficient of thermal expansion, such as aluminum or copper. The body 27 of the radiator has a fairly thick and uniform wall surrounding the substantially cylindrical portion of container 11 but is much 50 thicker at the top. A thick web 28 formed integrally with body 27 may be provided and may have metal inserts 29 in the form of supporting brackets, the ends 30 of which are adapted to be secured to a support 34. Either bracket may 55

function as the anode terminal for the tube. Radially disposed cooling fins 31 may be cast integrally with body 27 or be attached thereto. The radiator may have, in addition, a surrounding stack 35 to increase the circulation of air through the fins by natural convection.

Before attaching radiator 26 to tube 10 the latter should be degassed, filled with the desired ionizable medium, and permanently sealed, because degassing processes employ high temperatures (up to 1000° C.) which would injure or destroy the radiator, and in any event, prior attachment of the radiator would interfere with the tube-making processes.

15 In the embodiment illustrated in Fig. 1 the radiator is made separate from the tube and is attached thereto by pouring in a molten metal filling 32 having a higher coefficient of thermal expansion than the metal composing the evacuated container 11. Zinc and tin are suitable filling metals when chamber 11 is made of steel. For good heat conductivity it is essential that no part of the surface of envelope 11 at which substantial anode losses occur be flat or concave outwards. In Fig. 1 it will be noticed that all surfaces on which anode losses occur are convex outward. In a discharge tube of this sort the area over which the anode losses will be distributed depends on the pressure of the gas filling. It would probably cover the area above the top of cathode 15 with the intensity increasing toward the axis of the tube. For this reason the radius of curvature is decreased as the axis is approached. This radius of curvature taken in conjunction with the difference in thermal expansion of the material of the radiator filling and envelope results in intense casting strains when the filling material solidifies tending to collapse the dome of envelope 11. The intimate contact thus obtained by radial stress is essential to satisfactory operation, because any area of low local pressure results in severe gassing or even melting of the envelope 11 under load. Due to the lower heat conductivity of the zinc or tin filling 32 compared to copper or aluminum the thickness of the space to be filled is as small as is consistent with good casting practice.

Modifications of the Fig. 1 construction are possible; for instance, if desired the entire radiator may be cast on to the envelope 11 provided the latter is treated to withstand the temperature attained in casting without seriously affecting the properties of the tube. At the present time, plain steels are not available which can adequately resist the diffusion of hydrogen at the casting temperature of aluminum. To increase the life of the tube the steel may have a thin vitreous enamel coating on the outside. By the use of severe casting strains set up in the manner described it is possible to cast zinc or tin in such close contact with the enamel that heat is removed to the radiator during heavy load without damage to the tube, and good electrical contact is obtained with the steel.

To increase the temperature strains as much as possible the method of casting may be as follows: Radiator 26 is turned upside down and heated to about 400° C. Zinc or tin, in a separate crucible, is heated to melting temperature. The envelope 11 is warmed to 100° C. or so. Such molten metal in excess is quickly poured into the cup formed by the radiator and then tube 10 is forced down into the molten metal and held solidly until the latter is all solidified. Preferably radiator 26 is placed on a cool block of

metal during the casting process to insure the solidification of the molten metal around the nose of envelope 11 first and to prevent hidden voids in the filling metal. A groove 33 may be provided in the wall of container 11 to interlock the solidified metal with tube 10.

By this process it is believed the pressure set up causes plastic flow of the filling metal on cooling thus causing it to fill in minute crevices or roughness in the radiator casting and in the enamel coating on the tube. It is, of course, apparent that enamel is a poor conductor of heat and for this reason the coating must be made extremely thin so that the temperature drop across it will not be severe. Such large quantities of heat are involved that the conductivity of the container 11 tending to carry heat around any point of poor contact is negligible. So much heat must be transmitted that even in a thin layer of steel a very appreciable temperature drop will occur across this metal. Needless to say, the radiator must have a large thickness of aluminum or copper directly opposite the anode surface to provide sufficient cross section to conduct the heat away from the limited anode area and distribute it quickly to a path of much larger cross section.

By the decrease in radius of curvature toward the top of anode 11 as shown in Fig. 1 the heat flow is more or less radial at all points and results in a very rapid increase in the cross section of the heat conducting path as the heat is carried away from the anode surface. The cross section of radiator 26 is increased so much within 3 or 4 centimeters of heat travel from the surface of anode 11 that temperature drops are not serious. It is then only necessary to provide adequate cross section of attachment for the radiating fins 31. It is preferable to dispose the fins vertically relative to the mounting position of the tube in order to make all of them effective for cooling.

It will be apparent that a radiator of the type described dissipates most of its energy by convection rather than by radiation and that the velocity of the air through the fins can be increased if the stack 35 is provided to constrain the flow of heated air above the tube. This results in an increase in radiation but is often omitted because of space limitations.

Fig. 3 illustrates a modification wherein the web 28 and brackets 29 of Fig. 1 are omitted and the stack 35 has tabs 36 adapted to be secured to a support 37. The stack may be secured to the outer edges of some of the fins 31 by small screws 38, or in some other manner, so that the stack supports the entire structure.

The steel used for container 11 may be cold rolled or stainless steel. In some cases other metals may be used if they have the requisite strength and resistance to hydrogen diffusion at the temperatures employed.

For the radiator body the aluminum or copper may be alloyed with other metals. Alloys containing magnesium, nickel, zinc or cadmium also may be used if they have high heat conductivity and high coefficient of expansion. The melting point may be high for a precast radiator but it should be fairly low if cast directly on the container. The fins 31 may be cast as part of the radiator body or they may be of sheet copper having good heat conductive connection to a central metal body or die-casting.

For the filling metal, tin is preferred for its low melting point (234° C.) whereas zinc is pre- 75

ferred for its higher heat conductivity if its casting temperature (above 420° C.) does not have a deleterious effect upon the tube 10. Lead and cadmium may be used, or solder, or other alloys 5 containing one or more of the metals mentioned provided they have suitable melting points combined with good heat conductivity and high expansion coefficient. If the radiator is copper or an alloy thereof its inner surface may be "tinned" 10 beforehand and thus form a bond with the filling metal like the bond obtained by soldering or sweating.

The attachment of a radiator on a gaseous discharge tube as above described results in a ten-fold increase in the capacity of the tube to rectify current. For instance, a tube of the type 15 shown in Fig. 1 in which the container is about 3½ inches in diameter and 6 inches long can supply a load of 15 kilowatts at 110 volts when it is equipped with a radiator but without the radiator it cannot supply more than 1½ kilowatts 20 load.

A practical advantage of a precast radiator with a filling metal is that, when the electron tube 25 fails or is worn out it may be removed by melting the filling metal and then the radiator casting may be used with a new tube.

While the invention is particularly advantageous in connection with gaseous discharge tubes 30 it may also be used to advantage with high power high vacuum tubes and in general with electron tubes having metal or partly metal containers irrespective of the number or kind of contained electrodes, type of discharge, degree of 35 vacuum, or the nature of the gas or vapor filling. The invention also is applicable generally to sealed metal containers having a source of heat therein and requiring faster cooling than is obtained by natural radiation from the container 40 itself.

The terms "spheroid" and "spheroidal" as used in the specification and claims include "ellipsoid" or "ellipsoidal" or "conoid" or "conoidal."

While two specific embodiments of the invention 45 have been shown and described it should be understood that further modifications may be

made such as to meet different conditions or uses, and therefore the appended claims are intended to cover all modifications within the true spirit and scope of the invention.

We claim:

1. An electron tube comprising a cathode, an anode enclosing the cathode and being wholly spheroidal in shape over that part of the anode surface which receives the electron discharge, and a radiator having a heat conducting portion of higher co-efficient of expansion than that of the metal anode and having a spheroidal recess complementary to and fitted over the spheroidal anode and at the normal operating temperature of the tube being stressed in tension in all directions tangential to the recess surface to exert high inward pressure against all parts of the spheroidal surface of the anode over which it is fitted, which stress can be relieved only by temperature above the normal operating temperature of the tube. 10

2. An electron tube comprising a cathode, an anode enclosing the cathode and being wholly spheroidal in shape over that part of the anode surface which receives the electron discharge, a radiator having a heat conducting portion of higher co-efficient of expansion than that of the metal anode and having a spheroidal recess complementary to and fitted over the spheroidal anode and at the normal operating temperature of the tube being stressed in tension in all directions tangential to the recess surface to exert high inward pressure against all parts of the spheroidal surface of the anode over which it is fitted, which stress can be relieved only by temperature above the normal operating temperature of the tube, and a spheroidal liner interposed between the anode and the radiator, said liner being of metal relatively soft comparable to the anode and the radiator and having a melting point lower than that of the anode and the radiator and higher than that of the operating temperature of the tube. 20
